US00D654069S

(12) **United States Design Patent**
Kwon et al.

(10) **Patent No.:** **US D654,069 S**
(45) **Date of Patent:** **** Feb. 14, 2012**

(54) **MOBILE PHONE CASE**

(75) Inventors: **Jong-Chan Kwon**, Yongin-Si (KR); **Jun-Won Bae**, Yongin-Si (KR); **Sang-II Park**, Namyangjoo-Si (KR); **Hae-Jin Kim**, Seoul (KR); **Dae-Kyung Ahn**, Seoul (KR)

(73) Assignee: **Samsung Electronics Co., Ltd.** (KR)

(**) Term: **14 Years**

(21) Appl. No.: **29/390,798**

(22) Filed: **Apr. 29, 2011**

(30) **Foreign Application Priority Data**

Mar. 3, 2011 (KR) 30-2011-0008502

(51) **LOC (9) Cl.** **14-03**

(52) **U.S. Cl.** **D14/250**

(58) **Field of Classification Search** D14/250–253, D14/440, 203.3–203.7, 217, 496, 248; D3/201, D3/218, 269, 301, 273, 303; D13/103, 107–108; 220/4.02; 248/309.1; 361/679.56; 379/426, 379/433.11, 455; 455/575.1, 575.8; 190/100; 206/305, 320

See application file for complete search history.
